UNITED STATES PATENT OFFICE

ALBERT TILT, OF PATERSON, NEW JERSEY.

DESIGN FOR HANDKERCHIEFS.

Specification forming part of Design No. **11,203**, dated May 20, 1879; application filed April 22, 1879.
[Term of patent 3½ years.]

To all whom it may concern:

Be it known that I, ALBERT TILT, of the city of Paterson, in the State of New Jersey, have originated or designed a Pattern or Design for Handkerchiefs, of which the following is a full, clear, and exact description, reference being had to the accompanying photographic illustration, making a part of this specification.

My design relates more particularly to that description of handkerchiefs usually known as "figured-silk handkerchiefs;" and consists of the ornamentation of the central portion or body A of a handkerchief by embroidering or weaving upon it the design or arrangement of sprigs of ferns set forth and shown in the accompanying photographic illustration, the design on the portion of such body A not shown in such illustration being a duplication of that on the portion shown. Such design may be in colors different from the body A of the handkerchief, or they may be of the same

color, the one being of silk and the other of satin.

I have usually inclosed such central portion or body, A, with the design upon it, within a suitable border, in order to form a complete handkerchief, such border being shown in the accompanying illustration and designated therein by the letter B; but I do not claim such border as part of the design originated by me; but

What I do claim, and desire to secure by Letters Patent, is—

The design for a handkerchief, consisting, essentially, of the central portion or body, A, of sprigs of ferns, grouped substantially as described, and shown in the accompanying illustration.

ALBERT TILT.
